UNITED STATES PATENT OFFICE.

PEREZ M. STEWART, OF NEW YORK, N. Y.

BUILDING CONSTRUCTION.

1,068,544.

Specification of Letters Patent.

Patented July 29, 1913.

Application filed November 5, 1912. Serial No. 729,575.

To all whom it may concern:

Be it known that I, PEREZ M. STEWART, a citizen of the United States, and a resident of the borough of Manhattan, in the city, 5 county, and State of New York, have invented an Improvement in Building Construction, of which the following description, in connection with the accompanying drawings, is a specification, like characters 10 on the drawings representing like parts.

This invention relates to a concrete building construction and is herein shown as embodied in a roof construction for such buildings, which is especially applicable to concrete 15 buildings employed for refrigerating purposes, silk mills, and paper and pulp mills, wherein it is desired to obtain a maximum heat insulation.

The present invention has for its object 20 to increase the insulation of buildings of the character specified at a minimum expense. To this end, the concrete roof is provided with a layer or member of concrete, which is supported by a sheet or member 25 of corrugated material, and between these two members is interposed a suitable material for insulating the concrete from the whole or a part of the corrugated sheet.

A mixture of gypsum and cork or other 30 non-metallic dust, which is a poor conductor of heat and cold, forms a good insulating material, which may be used in plastic form to fill the valleys on the upper surface of the corrugated sheet or member. The valleys 35 formed on the under surface of the corrugated sheet may be covered by a layer or member of heat insulating material, such as a sheet of asbestos paper, cork board or the like, to form a series of air spaces which 40 add to the heat insulating properties of the building. While plain corrugated material may be used with good results, it is preferred to employ corrugated asbestos protected metal.

45 The particular features of this invention will be pointed out in the claims at the end of this specification.

The drawing represents in section a sufficient portion of a building construction 50 embodying this invention to enable it to be understood.

In the drawing is represented a preferred construction, which includes a corrugated sheet member *a*, forming valleys *b* on its 55 upper side and valleys *c* on its lower side. The members *a* are suitably supported by con-

crete beams *d* and may have their valleys *b* filled with a good insulator of heat and cold *e*, such as a mixture of gypsum and cork or other non-metallic dust. Above the corrugated sheet member *a* is located the layer or member *f* of concrete, which, in the construction shown in Fig. 1, rests on the insulator *e* and on the portions of the corrugated sheet between the valleys *b*. The corrugated member may have secured to its lower side a layer, sheet or member *g*, which may be cork board, asbestos paper or like heat insulating material, which closes the mouths of the valleys *c* and forms air spaces 70 *i* thereof. The concrete beams *d* may be enveloped by sheet metal *h* and by the cork board *g*.

By reference to the drawing, it will be seen that the concrete layer or member *f* which, in itself is a poor insulator of heat and cold, is highly insulated against external heat and cold by the insulating material *e* which fills the valleys *b* of the corrugated member *a* and by the air spaces *i* 75 formed by the layer or member *g* closing the valleys *c* of said corrugated sheet. Furthermore the insulation obtained by the air spaces *i* and the material *e* filling the valleys *b*, enables a very thin cork board to be 80 used, which enables the desired insulation to be obtained at a minimum expense. It is also preferred to use corrugated asbestos protected metal for the corrugated member, as by so doing, there is obtained the benefit 85 of the sheets of asbestos and the asphalt with which they are cemented to the opposite surfaces of the metal sheet, but it is not desired to limit the invention in this respect as good results are obtained with 90 plain corrugated sheets of metal or non-metallic material.

It will be understood that the various layers or members are secured together in any suitable manner, and as the method 100 of fastening the parts together does not form any part of the invention no specific method is shown or deemed necessary to a proper understanding of the invention. From the above description, it will be seen 105 that a highly insulated and non-condensing concrete building construction is obtained, which is especially applicable as a roof structure for buildings used for cold storage, silk mills, paper and pulp mills and 110 like buildings, but which may also be used as a wall or floor construction.

Claims.

1. A concrete construction for buildings embodying a corrugated sheet, a mixture of gypsum and non-metallic dust located in the valleys on the upper surface of said corrugated sheet, a concrete member above the corrugated sheet, and a layer of cork board covering the valleys on the under side of said corrugated sheet to form air spaces, substantially as described.
2. A concrete construction for buildings embodying a corrugated member, heat insulating material located in the valleys on

the upper surface of said corrugated member, a concrete member above the corrugated member, and a layer of heat insulating material covering the valleys on the under side of said corrugated member to form air spaces, substantially as described. 15

In testimony whereof, I have signed my 20 name to this specification in the presence of two subscribing witnesses.

PEREZ M. STEWART.
